UNITED STATES PATENT OFFICE.

HENRY EDWARD HORN, OF DENVER, COLORADO.

BACK-STAY FASTENING FOR CARRIAGE-TOPS.

SPECIFICATION forming part of Letters Patent No. 368,473, dated August 16, 1887.

Application filed February 16, 1887. Serial No. 227,786. (No model.)

To all whom it may concern:

Be it known that I, HENRY EDWARD HORN, a citizen of the United States, residing at Denver, in the county of Arapahoe and State 5 of Colorado, have invented a new and useful Device for Fastening the Back-Stays of Carriage-Tops, of which the following is a specification, reference being had therein to the accompanying drawings, in which similar letters refer to corresponding parts.

My device consists of a plate set within the back part of the carriage-seat on each side and fastened by means of screws, said plate being provided with a number of lugs on the 15 inner side, these lugs being provided with threaded openings for the reception of screw-buttons, as hereinafter more fully described.

In the drawings, Figure 1 is a plan view of my improved device. Fig. 2 is a side elevation of the device, showing the carriage-back in section. Fig. 3 is a sectional end view taken on the line $x-x$, Fig. 2. Fig. 4 is an end view of the carriage back and stay, the fastening-plate and the threaded portion of the screw-button being shown in dotted lines. Fig. 5 shows the screw-button. Fig. 6 is an enlarged rear view of the carriage back and stay, showing the manner of fastening the stay with the screw-buttons.

30 The ordinary method of fastening the back-stays of carriage-tops is by means of nails driven through the stays into the wooden portion of the back of the carriage-seat. This is done after the carriage is painted and varnished, and consequently the varnished surface is often checked in driving the nails. Furthermore, whenever a carriage is taken apart for shipment, or for any other purpose, the nails fastening the stays must be removed. It 35 will be readily observed that after these stays have been taken off and refastened a few times the back of the carriage-seat where the nails have been driven will be so badly cut up or perforated with nail-holes that it will not hold a 40 nail securely.

The object of my device is to obviate the necessity of nailing the stays, thereby avoiding the difficulties resulting therefrom, and which I have just mentioned. This object I accomplish in the manner shown in the drawings, and hereinafter described.

A is a plate constructed of metal or any suitable material, and provided with lugs A', molded on its inner surface.

Plate A is provided with threaded openings 55 A², which extend through lugs A', as shown in Fig. 3, and by dotted lines in Figs. 2 and 4.

Plate A is set within the wooden back of the carriage-seat, as shown in Figs. 2, 3, and 4, and fastened by means of screws inserted in 60 the openings A³, Fig. 1.

B B, &c., are screw-buttons, made of sufficient length to extend through stay C, plate A, and lugs A', as shown by dotted lines in 65 Fig. 4.

The object of lugs A' is to hold screw-buttons B securely in place by giving them a threaded opening, A², of considerable length.

In defining my invention with greater clearness, I would state that I am aware that it is 70 not new to form the strap of a hinge with screw-holes having a re-enforcement of metal or a boss around the same; and I do not claim, broadly, a plate having such re-enforced holes. In my invention it will be seen that the plate 75 A has independent screw-holes, which receive screws that attach it to the carriage, while the internally-threaded lugs or bosses A' are socketed to receive the buttons B.

Having thus described my invention, what I 80 claim, and desire to secure by Letters Patent, is—

1. As a new article of manufacture, the plate A, having one set of screw-holes for attaching it to the carriage, and having also 85 low internally-screw-threaded lugs or bosses A, for receiving the screw-threaded shanks of the buttons, as shown and described.

2. A device for fastening the back-stays of carriage-tops, consisting of plate A, provided 90 with lugs A', and threaded openings A², in combination with screw-buttons B, substantially as described, and for the purpose set forth.

3. A device for fastening the back-stays of 95 carriage-tops, consisting of plate A, provided with lugs A', and threaded openings A², said plate being suitably attached to the back portion of the carriage-seat, in combination with screw-buttons B, or their equivalent, substantially as described, and for the purpose set 100 forth.

HENRY EDWARD HORN.

In presence of—

F. H. JOHNSON,
L. M. SLEETH.
